UNITED STATES PATENT OFFICE.

A. BUTTLES SMITH, OF NEW YORK, N. Y., ASSIGNOR TO HIMSELF, JOHN W. DEXTER, EDWARD DEXTER, AND ERASTUS G. KNIGHT, OF SAME PLACE.

STOCK-INDICATOR.

SPECIFICATION forming part of Letters Patent No. 358,896, dated March 8, 1887.

Application filed February 2, 1885. Renewed January 26, 1887. Serial No. 225,580. (No model.)

To all whom it may concern:

Be it known that I, A. BUTTLES SMITH, a citizen of the United States, residing in the city, county, and State of New York, have 5 invented a new and useful Stock-Indicator, of which the following is a specification.

My invention relates to certain improvements in the stock-indicator patented to me July 8, 1884, No. 301,763, whereby the results 10 sought to be accomplished by said patented indicator are rendered more satisfactory, as will be hereinafter shown.

In the accompanying drawings, Figure 1 is a front view of a stock-indicator with my invention, the upper covering of it being shown 15 in section in order to exhibit the inclosed parts. Fig. 2 is a side view of inner mechanism of the same, the housing thereof being sectioned. Fig. 3 is an inverted plan view of the con- 20 trolling-magnets and a portion of the clock-work mechanism employed in connection therewith. Fig. 4 is a top view of the reversing mechanism and a portion of the escape mechanism as seen above the housing. Fig. 5 is a 25 detail view of the two magnets and their immediate or direct connections with the clock and reversing mechanisms, a portion of the mechanism being sectioned. Fig. 6 is a detail view, partly in section, of the escape mech- 30 anism. Fig. 7 is a horizontal section in the line $x-x$ of Fig. 1, and Fig. 8 is a detail view of a modified construction of the escapement shown in Fig. 6.

In the drawings, A represents a suitable in- 35 closure or housing of the magnets and clock mechanism; B, a clock mechanism; C, an escape-magnet; D, a reversing-magnet; E, a reversing mechanism, and F an exhibit device.

The clock mechanism B, which is to be 40 wound up in the ordinary manner, is of usual construction, and consists of a drum-wheel, b, cord b', weight b'', and an ordinary train, one wheel, b³, of which latter is coupled with an escape-wheel, b⁴, having eight (8) steps, b⁵, and 45 a stopping-pin, b⁶. An armature-lever, c, carrying the armature c' of the escape-magnet C, is pressed by means of an ordinary tension-spring, c⁷, against the periphery of the escape-wheel b⁴, and thus engages with the steps b⁵ in

the manner and under certain conditions as 50 will be hereinafter described. An auxiliary curved hook-pawl, c², is pivoted at c³ to the armature-lever c and pressed by a spring, c⁴, upon a guide-plate, c⁵, on the pawl-stand c⁶, the hooked end of which pawl c² is moved in 55 range with the pin b⁶ of the escape-wheel when the armature lever c is attracted by its magnet, thereby moving the bulged portion c⁸ of the pawl c² upon the guide-plate c⁵ and elevating the pawl. The pin b⁶ is so placed upon 60 the escape-wheel b⁴ and with respect to the pawl c² that when the escape-wheel is stopped by the said parts the fractional portion of the exhibit device F displays zero instead of one of the fractions, as will be seen. 65

The wheels b³ b⁴ are fastened to a shaft, d, to which a sleeve, d', is loosely fitted. The sleeve d' has two bevel-wheels, e e', fastened to it, which alternately gear into a horizontal bevel-wheel, e³, according to the position of 70 the sleeve. The position of the sleeve d' is regulated by a forked head, d³, of an armature-lever, d⁴, fitted in a groove, d⁵, of the sleeve. As the magnet D is charged, and attracts the armature d³ of the lever d⁴ the sleeve d' is 75 drawn along, and the wheel e' engages with the wheel e³, and as the magnet is released a spring, d⁶, moves the lever d⁴ and sleeve d' back to their former places, and the wheel e is thus caused to engage with the wheel e³. The 80 stroke of the sleeve d' is adjusted by means of a set-screw, d⁷, in one of the stands a, supporting the shaft d, and the sleeve d' is, by means of a longitudinal key, d⁸, caused to revolve with the shaft d and wheel b³ of the clock- 85 train.

To the hub e⁴ of the wheel e³ a drum, f, of the exhibit device F is fastened and revolves with it. This drum f has 0 and the fractions $\frac{1}{2}$, $\frac{1}{3}$, $\frac{2}{3}$, $\frac{1}{4}$, $\frac{3}{4}$, $\frac{1}{5}$, $\frac{4}{5}$ marked upon its cylindrical 90 surface, so that 0 is in exhibiting position when the pin b⁶ of the escape-wheel b⁴ is arrested by the pawl c², as aforesaid. The wheel e³ and drum f are loosely fitted to an upright pin, f', which is inserted into the bearing-stand e⁵ of 95 the wheel e³, and there fastened by a transverse pin, e⁶. Above the drum f a drum, f², having the numbers 1, 2, 3, 4, 5, 6, 7, 8, 9, 0 on its cylin-

drical surface, is loosely fitted on the pin f' , and above the drum f^2 a drum, f^3 , having the numbers 1, 2, 3, 4, 5, 6, 7, 8, 9 and a blank space on its cylindrical surface, is loosely fitted upon the 5 said pin f' . The drum f^2 is operated by the drum f , and the drum f^3 is operated by the drum f^2 in the same manner and by the same means as described in my aforesaid patent, the drum f^2 exhibiting the units, and the drum f^3 exhibiting the tens. These drums are surrounded by a slotted casing, f^4 , of opaque material, which may be provided with a coating of paint without luster to avoid dazzling the eye of the observer, and a strip of straight flat glass, f^5 , 15 of proper width is suitably inserted into the casing f^4 , in order to exhibit the numbers on the drums in vertical rows. With this arrangement the observer is enabled to distinctly and speedily read off the exhibited numbers 20 of the respective drums, even if only allowed a side glance at the same, and no disadvantage arising from a cylindrical glass case will be experienced.

The conducting-wires of the magnets C and 25 D are connected with two separate ordinary switches placed between them and two ordinary electrical batteries. Other connecting-wires are used to connect the said magnets with corresponding magnets of other stock-indicators in the same manner as described in my aforesaid patent, so that a number of stock-indicators at different places are operated simultaneously by means of the said ordinary switches.

30 The operation of my stock-indicator herein described is greatly simplified as compared with my former patented invention, inasmuch as one quick motion of the escape-armature is only necessary to change the exhibit one-eighth, more or less, while one prolonged charge of the escape-magnet will cause all the stock-indicators to show 0 on the drum f . This latter movement is always resorted to when there is a suspicion of some failure in the operation of one or more indicators of a whole line of indicators while the quotations are going on. When a quotation-number is to be changed upward, the operator quickly moves the escape-switch forward and back, and 45 thereby effects a change or rise of one-eighth on the drums f of a circuit of indicators, or along the whole line. If the change of quotation is one-fourth, he makes another back-and-forward motion in addition to the first, and 50 the drums f will exhibit a difference or rise of one-fourth, and so on. If the quotation is a fall of one-eighth, the operator moves the reversing-switch forward and holds it in that position while he operates the escape-switch 55 in the manner above described, and the result is a fall in the value of the exhibited numbers on the drums f , as will be seen.

The steps b^5 of the wheel b^4 constantly bear upon the armature-lever c by means of the 60 operating-weight b^2 , as long as the magnet C is not charged. The above-described quick

movement of the escape-switch charges the magnet C for a moment, and the lever c is caused to make a momentary oscillation from and toward the escape-wheel b^4 , thereby releasing the engaged step b^5 and allowing the escape-wheel to revolve before the returning armature-lever c can rearrest the same step b^5 , so that the wheel moves on until the next step b^5 is stopped by the returning armature-lever c . 75

When a failure of operation along the line is suspected or discovered, the operator charges the magnet C by means of the escape-switch, and keeps it charged, whereby all the escape-wheels along the line are caused to revolve without stopping at any of the steps b^5 until the pins b^6 come in contact with the pawls c^2 and are thus stopped. Then he releases the escape-magnet C, whereupon the armature-lever c is moved 85 against the wheel b^4 and caused to arrest the next arriving step b^5 of the escape-wheel. The drums f now all along the line exhibit 0, or zero. The operator now proceeds again to telegraph the quotations in the above-described manner. 90

Instead of operating the drum-wheel by a weight, b^2 , it might be operated by an ordinary clock-spring without departing from the principle of my invention. 95

The modification represented by Fig. 8 relates to the escape motion, and shows the escape-wheel G fastened to the hub e^4 of the wheel e^3 , and, as this wheel has a forward-and-backward motion, straight notches g are provided, into which the armature-lever c enters and stops the wheel. The pin b^6 is placed on the wheel G , so that when coming in contact with a lug, g' , on the armature-lever c the wheel G is stopped and the drum f exhibits zero. This lug g' is in the path of the pin f^6 only when the escape-magnet C is charged and the armature-lever c is removed from the wheel G , as shown by dotted lines. 100

As indicating the prior state of the art, reference is here made to Letters Patent numbered, respectively, 154,309, 250,490, 267,437, and 301,763, and I would state that I claim under this patent nothing embraced by said patents. 110

115 What I claim is—

1. The combination of the revolving drum f , escape-wheel b^4 , suitable other clock mechanism, pin b^6 , armature-lever c , auxiliary pawl c^2 , guide c^5 , and magnet C, whereby the drum f 120 can be adjusted to zero-point, substantially as described.

2. The combination of the magnet D, armature-arm d^4 , having forked head d^3 , revolving and reciprocating sleeve d' , having groove d^2 and wheels e^3 , shaft d , wheel e^3 of an exhibiting-drum, f , and a clock mechanism for revolving shaft d , substantially as and for the purpose described. 125

3. The combination of the exhibit device F, 130 comprising one or more back-and-forward moving drums, as $f^2 f^3$, having numbers on their

peripheries, a clock mechanism, B, one wheel of which is coupled with an escape-wheel, b^4 , having a stop-pin, b^6 , an escape-magnet, C, for operating the escape-wheel b^4 and pin b^6 ,
5 a reversing mechanism, E, driven by the clock mechanism B, and a reversing-magnet, D, for operating the reversing mechanism and

thereby producing back and forward movements of the drum f, substantially as and for the purpose described.
